UNITED STATES PATENT OFFICE.

IRVING G. SCOTT AND MAUD C. FOX, OF NEW YORK, N. Y.

DESIGN FOR A WALL POT HOLDER.

Application filed February 14, 1929. Serial No. 20,069. Term of patent 3½ years.

To all whom it may concern:

Be it known that I, IRVING G. SCOTT, a citizen of the United States, residing at New York city, in the county of New York and State of New York, and I, MAUD C. FOX, a citizen of the United States, residing at New York city, in the county of New York, and State of New York, have jointly invented a new, original, and ornamental Design for a Wall Pot Holder, of which the following is a specification, reference being had to the accompanying drawing, forming part thereof, in which—

We claim:

The ornamental design for a wall-pot holder as shown.

IRVING G. SCOTT.
MAUD C. FOX.
